(57) **CLAIM**

The ornamental design for a transaction card, as shown and described.

DESCRIPTION

The FIGURE is a front view of the transaction card showing our new design.

All other surface(s) or portion(s) of the transaction cards not shown in the FIGURE or otherwise described in the specification (including the outer edge and the back of the financial transaction card) form no part of the claimed design.

The transaction card is interpreted to be flat with an applied design.
